WALKER STANSELL, OF MEMPHIS, TENNESSEE.

BUCKET-CATCH.

1,121,415.

Specification of Letters Patent.

Patented Dec. 15, 1914.

Application filed March 26, 1914. Serial No. 827,422.

To all whom it may concern:

Be it known that I, WALKER STANSELL, a citizen of the United States of America, residing at Memphis, in the county of Shelby 5 and State of Tennessee, have invented certain new and useful Improvements in Bucket-Catches, of which the following is a specification.

The present invention relates to an improved bucket catch and is designed particularly for use in connection with overhead conveyers employing a bucket and supporting traveling carriage.

The primary object of the invention is to 15 provide an improved releasing device to disengage the supported bucket from its carriage by a simple manipulation of a tripping mechanism that is in itself extremely simple in construction and operation, but 20 accurate and efficient in performing its required functions.

The invention consists essentially in certain novel combinations and arrangements of parts of the bucket latch or catch and the 25 tripping or releasing mechanism as will hereinafter appear.

In the accompanying drawings I have 30 illustrated one complete example of the physical embodiment of my invention constructed according to the best mode I have so far devised for the practical application 35 of the principles of the invention.

The drawing shows in perspective a traveling carriage supported upon a rope track, 35 with the bucket suspended from the carriage, and for convenience of illustration parts of the devices are shown broken away and some parts are shown in section.

In the exemplifying structure shown in 40 the drawing I have utilized a well known type of traveling carriage comprising the frame 1 which is adapted to travel back and forth upon the rope track 2 by means of the sheaves 3, 3, 4, journaled in the frame and 45 adapted to run on the rope or cable 2.

The bucket 5 is of conventional type and is hoisted to the carriage by means of the hoisting rope 6 having one end attached to the carriage at 7 and passing over the pulley 50 8 of the carriage and under the sheave 9 of the bucket. When the bucket is empty and returning for a load, it is directly supported from the carriage by means of a fixed, metallic sleeve 10 which may be cast or 55 wrought iron as required and is rigidly sup-

ported and fixed by means of the transverse bars 11 11 that are bolted to the lower frame bars of the carriage. This metallic sleeve is cylindrical and open at the top, but is provided with a lower portion 12 which is 60 conical or flaring to an open bottom. At the junction of the cylindrical and conical portions of the tubular member or sleeve, an annular, interior, ring or shoulder 13 is 65 formed which provides a flange extending completely around the inner bore of the sleeve, and the decreasing diameter of the flaring lower portion of the hollow member or sleeve terminates at this flange. A pair of yieldable arms or spring latch bars 14 70 15 are designed to co-act with the flanged sleeve. These two arms or latch bars are arranged vertically and parallel and are joined by the angle plates 16 16 bolted thereto. At their lower ends these two bars are 75 pivoted in the head 17 of a plate 18, which as clearly shown is bolted to the bucket, a bolt 19 and nut 20 being employed for this purpose. These latch bars also provide a bearing for the bolt 21 which forms the 80 journal for the sheave 9 for the hoisting rope. At their free ends these latch bars are formed with heads or hooks 22, and the extreme ends of the hooks are beveled at 23 to form a cam or wedge surface. The latch 85 bars from their point of connection at the angle plates 16 to their free ends are of resilient or yielding, springy, characteristic, and when properly acted on may be bent toward each other, to free the supported 90 bucket from the carriage.

For the purpose of disengaging the hooks and releasing the bucket I employ a hollow metallic plunger 24, located within the upper open end of the sleeve and movable 95 therein. This plunger is similar to an inverted cup and its lower annular edge is inferiorly beveled at 26 to co-act with the beveled edges of the heads or hooks on the ends of the resilient latch bars 14, 15 to move the 100 same toward each other. The plunger is actuated by a tripping lever 27 which is fulcrumed at 28 in the carriage frame and provided with a trip rope 29 within easy access of an operator. One end of the trip lever is 105 pivoted by the bolt 30 in the slotted end 31 of a pivoted link 32. This link is pivoted on the bolt 33 supported transversely in the frame and is pivoted at 34 to the upper end of the hollow plunger, and a spring 35 at 110

tached to the link and a cross bar in the frame tends to pull down that end of the link to which it is attached.

The operation of the device will be readily understood from the drawing. The bucket is revoluble, as shown by the arrows, on the hooks 22 which may slide around on the shoulder 13, and this motion is desirable in some instances to absorb strains. The bucket is shown as supported on the latch bars. When it is desired to unlatch the bucket, a pull on the trip rope 29 will cause the lever and link to swing on their fulcrums and depress the plunger 24. The bevel edge 26 of the plunger engages the complementary edges or faces 23 of the hooks 22 and thus squeezes the latch bars together freeing the hooks from the shoulder 13, and the bucket is freed. The bucket is latched as it is lifted by the hoisting rope and the flaring end 12 of the sleeve guides

the latch bars to their position upon the flange or shoulder 13 as will be understood.

Having thus fully described my invention, what I claim as new and desire to secure by Letters Patent is:

The combination with a carriage and a fixed open end cylindrical sleeve having an interior annular shoulder, of a hoisting bucket with resilient hooked latch bars engaging said shoulder, a beveled plunger above the hooked latch bars and movable in the sleeve, a portion of the sleeve having an outwardly flaring interior wall for guiding the latch bars thereto, and means for lowering the plunger to disengage the latch bars.

In testimony whereof I affix my signature in presence of two witnesses.

WALKER STANSELL.
